DISPENSER HEAD FOR A PRESSURIZED CONTAINER

Haus Grothoff, Valbert, Germany, assignor to Perfect-Ventil G.m.b.H., Dortmund-Koerne, Germany

Filed Oct. 5, 1972, Ser. No. 295,367

Term of patent 14 years

Int. Cl. D9—07

U.S. Cl. D9—258

FIG. 1

FIG. 2

FIG. 3

FIG. 4

FIG. 5

FIG. 1 is a perspective view of a dispenser head for a pressurized container showing my new design;

FIG. 2 is a rear perspective view thereof;

FIG. 3 is a rear elevational view;

FIG. 4 is a front elevational view; and

FIG. 5 is a top plan view.

I claim:

The ornamental design for a dispenser head for a pressurized container, substantially as shown and described.
